THOMAS J. McCORMICK AND ROBERT E. LINN, OF DETROIT, MICHIGAN; SAID LINN
ASSIGNOR TO SAID McCORMICK

DESIGN FOR A TIRE COVER

Application filed March 2, 1931. Serial No. 38,908. Term of patent 14 years.

To all whom it may concern:

Be it known that THOMAS J. McCORMICK and ROBERT E. LINN, citizens of the United States, residing at Detroit, county of Wayne, State of Michigan, have invented a new, original, and ornamental Design for Tire Cover, of which the following is a specification, reference being had to the accompanying drawings, forming part thereof.

Fig. 1 is a perspective view of the tire cover, showing our new design.

Fig. 2 is a section on line 2—2 of Fig. 1.

The dominant feature of our design consists of the body portion of dark fabric contrasting in color with the highly polished beaded elements.

What we claim is:

The ornamental design for a tire cover, substantially as shown and described.

In testimony whereof, we sign this specification.

THOMAS J. McCORMICK.
ROBERT E. LINN.
